(57) **CLAIM**

The ornamental design for a “box for containing and dispensing fluid contained in a pouch therein,” as shown and described.

DESCRIPTION

FIG. 1 is a right side perspective view taken from the side and showing a first embodiment of our new design; FIG. 2 is a left side perspective view taken from the rear thereof;

FIG. 3 is a right side elevational view thereof;

FIG. 4 is a front elevational view thereof;

FIG. 5 is a left side elevational view thereof;

FIG. 6 is a rear elevational view thereof;

FIG. 7 is a bottom plan view thereof;

FIG. 8 is a top plan view thereof;

FIG. 9 is a right side perspective view taken from the side and showing a second embodiment of our new design; FIG. 10 is a left side perspective view taken from the rear thereof;

FIG. 11 is a right side elevational view thereof;

FIG. 12 is a front elevational view thereof;

FIG. 13 is a left side elevational view thereof;

FIG. 14 is a rear elevational view thereof;

FIG. 15 is a bottom plan view thereof; and,

FIG. 16 is a top plan view thereof.
